UNITED STATES PATENT OFFICE.

J. PURCELL BAKER, OF NEWARK, NEW JERSEY.

DESIGN FOR A BUTTON AND AN ORNAMENT THEREFOR.

SPECIFICATION forming part of Design No. 12,359, dated July 12, 1881.

Application filed May 7, 1881. Term of patent 3½ years.

To all whom it may concern:

Be it known that I, J. PURCELL BAKER, a citizen of the United States, residing in the city of Newark, in the county of Essex and State of New Jersey, have invented a new Design for Buttons, fully described and represented in the following specification and the accompanying drawings, forming a part of the same.

10 Figure 1 is a view of the face of a button ornamented by my design; and Fig. 2 a section of the same across its center line.

The face of the button is round, and upon it are shown four ornaments composed of a flat 15 six-leaved disk of metal, lettered *a*, having a stud or knob in the center, lettered *b*. The section of the button is presented in Fig. 2 to show the pyramidal shape of the stud, which is shown flattened upon six sides, to produce 20 reflecting-facets. In practice, the disks *a* are made of polished metal, covered with a transparent-colored varnish, so that they exhibit both color and metallic luster.

The studs *b* are, in practice, the polished

heads of steel rivets, whose glitter contrasts 25 most brilliantly with the colored disks, as they project above the surface of the latter and have a higher luster, due to the substance of which they are made.

I am fully aware that it is not new to apply 30 metallic disks to surfaces for ornamentation, nor to employ rivet-heads as decorations by themselves; but as the essential feature of my design is the combination of the two, respectively colored and polished, as described, 35

I claim—

The design consisting of the button provided with the ornaments *a b*, consisting of the six-leaved colored disk having the polished and uncolored metallic stud in the center, substantially as herein shown and described. 40

In testimony whereof I have hereunto set my hand in the presence of two subscribing witnesses.

J. PURCELL BAKER.

Witnesses:

THOS. S. CRANE,
WILLIAM HAWKINS.
